UNITED STATES PATENT OFFICE.

EDWIN F. GUTH, OF ST. LOUIS, MISSOURI.

LIGHTING FIXTURE.

Application filed August 17, 1926. Serial No. 129,677.

My invention relates to the art of illumination, and particularly to devices adapted to receive a light source and distribute the rays therefrom in desired and predetermined 5 manner.

The object of my invention is to provide a lighting fixture adapted to function in a manner, not only to give off a maximum light efficiency from the source, but also to distribute 10 the rays in such way as to produce a maximum efficiency for the general purpose for which it is adapted.

Combined with the above purpose, it is my object to produce a device having substantially 15 all of the advantages of the so-called "enclosed glass units", but at the same time to leave the neck of the lamp entirely exposed, so that there is no modifying means whatsoever between the neck of the lamp and the 20 side walls of the room, above the plane of the reflector which I use.

A further object is to produce, in a lighting fixture of the type above set forth, a combination support for both a reflector and a globe, the support being spaced, or suspended, from 25 the socket support, so as to leave the neck of the lamp used in the fixture entirely exposed.

A further object is to produce such a fixture from a combination of elements, associated together, which is adapted for practicability (for compactness) in shipping, installing, and maintaining.

A further, and very important, object is to provide an enclosed incandescent lighting unit, in which there will be a proper air circulation at the neck and the base of the lamp.

My invention consists of certain details of construction, hereinafter set forth, pointed out in my claim, and illustrated in the accompanying drawing, in which

Fig. 1 shows a side elevation of my device, a part of the same being in section; and

Fig. 2 shows a bottom view of my device, a part of the same being broken away.

In the accompanying drawing, reference numeral 10 is used to indicate a support for a socket 11, which receives a lamp 12. This support 10 is secured to any ordinary junction box in any desired manner, either by suspension means to the ceiling, or direct to the ceiling, or to a canopy interposed between, the essential feature only being that there is a support for socket 11.

The numeral 13 indicates a reflector, preferably circular in conformation and orificed

centrally at 14, to permit the projection there-through of the neck 15 of the lamp 12. The reflector 13 is secured to the socket support 10, preferably by means of metal strips 16, but it is obvious any form may be employed for 60 securing the reflector 13 to the socket support 10, just so that it provides for positioning and suspending the reflector 13 at substantially the desired distance below the socket support 10.

The reflector 13 is also provided with means 65 17 to support the globe 18. In the drawing, this means 17 is shown in a specific manner, but it is understood that any satisfactory securing means may be employed, the function 70 of the reflector 13 being also intended to include the function of securing the globe 18.

In the drawing, I have shown a diffusion glass cup 19, mounted above the neck 15 of the lamp 12, the function of this cup 19 being to 75 diffuse the rays of light immediately above the lamp 12, so as to relieve the ceiling of the room of bright circular rings which might otherwise be projected thereon. However, this is not necessary nor essential, but might 80 in some instances be desired.

The reflector 13, as shown in its combination with the other elements, closes the top of the globe 18, except for that orifice 14 through which the neck 15 of the lamp 12 projects. This orifice 14 is preferably wide enough to 85 leave a small space between the neck 15 of the lamp 12 and the edge of the orifice 14, and this assists in providing for proper ventilation in the lamp.

My fixture combines the following elements: A reflector, a globe depending therefrom, a support receiving and positioning both the reflector and the globe in proper relationship, an orifice in the central part of 95 the reflector, a lamp, the neck of which is projected upwardly through the orifice in the reflector to a seat in a socket, the reflector being spaced from the socket and permanently positioned thereto.

In my drawing, I have shown specified means for accomplishing these purposes, but I want it understood that different means may be employed without at all varying my invention, which, stripped to its basic intent, 105 is to produce a lighting fixture in which a reflector and a globe are spaced below a socket and properly supported, the neck of the lamp, above the reflector, being left exposed so that light rays emanating therefrom will not be 110

decreased in efficiency by absorption in passing through any modifying means, but will be projected outwardly and upwardly to the walls and ceiling of the room.

5 My fixture is so constructed that while the neck of the lamp is not impaired in its efficiency, as above set forth, it nevertheless cannot be seen from below the fixture, for the eye of the observer is shielded therefrom by
10 the reflector, and also by the globe, which is, obviously, preferably of diffusion glass. The reflector will, preferably, be of opaque material, but this is not strictly essential.

Having thus described my invention, what

I claim, and desire to secure by Letters Patent 15 of the United States is:

In a lighting fixture the combination of a socket, a cover therefor, a bulb in the socket, a shallow diffusing cup between the bulb and cover, supporting arms secured to the cover 20 and extending below the diffusing cup, an annular reflector on the arms, said reflector closely surrounding the neck of the bulb and a globe supported from the reflector surrounding the lower part of the bulb below the reflector. 25

EDWIN F. GUTH.
